UNITED STATES PATENT OFFICE.

WILLARD T. CASE, OF NEW BRUNSWICK, NEW JERSEY, ASSIGNOR TO DELTOX GRASS RUG COMPANY, OF OSHKOSH, WISCONSIN, A CORPORATION OF WISCONSIN.

DESIGN FOR A WOOL FIBER RUG.

60,777.

Specification for Design. Patented Apr. 11, 1922.

Application filed February 4, 1922. Serial No. 532. Term of patent 7 years.

To all whom it may concern:

Be it known that I, WILLARD T. CASE, a citizen of the United States, residing at New Brunswick, in the county of Middlesex and State of New Jersey, have invented a new, original, and ornamental Design for a Wool-Fiber Rug, of which the following is a description, reference being had to the accompanying drawing, forming part thereof.

The drawing is a plan view of one corner portion of a wool fiber rug showing my new design.

I claim:

The ornamental design for a wool fiber rug, as shown.

WILLARD T. CASE.
